MINIATURE UPRIGHT PIANO

Gustaf Waldemar Lundholm,
Stockholm, SwedenApplication June 8, 1932, Serial No. 616,054
In Sweden June 16, 1931

REISSUED

2 Claims. (Cl. 84—174)

The present invention relates to an improvement in miniature upright pianos in which the keyboard is located above the soundboard and the iron frame of the instrument, and the strings 5 and the piano action or hammer mechanism are located behind said frame and below the keyboard. In instruments of this kind as hitherto constructed the mechanism is carried by the side walls of the piano. This arrangement has the 10 disadvantage, however, that if the side walls warp, as might easily happen, the mechanism is displaced from its proper position with relation to the strings.

The present invention has primarily for its purpose to obviate this disadvantage, and it consists principally in that the iron frame is provided with rearwardly projecting brackets or arms which serve to support the mechanism which may thus be mounted in place independently of the 20 side walls of the piano. In this way it is ensured that the mechanism is always retained in correct position relatively to the strings. From the point of view of manufacture it is also a great advantage that the entire instrument can be assembled 25 before the side walls are fixed to the same. The brackets may suitably be provided with pivots or the like on which the mechanism is pivoted so that it may be swung rearwards for the purpose of facilitating intonation of the piano.

30 A constructional form of the invention is illustrated by way of example in the accompanying drawing. The drawing shows a vertical section of a piano constructed in accordance with the invention.

35 Referring to the drawing, 1 denotes the keyboard, and 2 denotes the keyboard bottom which is fixed by means of screws direct to the wrest plank 3, 4 denotes the soundboard which forms simultaneously the front wall of the piano, 5 denotes the iron frame, 6 the strings and 7 the tuning pegs which serve for tuning the strings, and which traverse the wrest plank 3 so that the tuning key can be applied to their forward or left-hand ends as viewed in the drawing, in order 45 to facilitate the tuning. The piano action or hammer mechanism 8, which is of the usual construction, is positioned behind the iron frame 5 below the keyboard and is actuated by the keys of the latter in a well-known manner by means 50 of metal wires 9 or other suitable connecting members. According to the invention the iron frame 5 is provided with two rearwardly projecting brackets 10, one at each side, said brackets being provided with pivots 11 on which the 55 frame 12 supporting the mechanism is pivoted.

By this arrangement the entire mechanism may be swung rearwards, to the right in the drawing, on the pivots 11 when the piano is to be intoned so that this work is considerably facilitated. The provision of the brackets 10 for supporting the mechanism ensures that the mechanism is retained in its correct position relatively to the strings 6, and that the entire instrument can be assembled and intoned before the side walls 13 are affixed.

The constructional form above described and illustrated in the drawing is only to be regarded as an example and may, of course, be modified in several respects as regards its details without departing from the principle of the invention. 70 For instance, instead of making the brackets 10 integral with the iron frame 5, they may be made as separate pieces and may be secured to the frame by means of screws or the like.

I claim:

1. In a miniature upright piano, the combination of a vertical iron frame, a soundboard, a keyboard above said iron frame and soundboard, strings attached to said iron frame on the rear side of the same below said keyboard, said frame 80 being provided with rearwardly projecting brackets, and a piano action supported by said brackets on the rear side of said frame below said keyboard.

2. In a miniature upright piano, the combination of a vertical iron frame, a soundboard, a keyboard above said iron frame and soundboard, strings attached to said iron frame on the rear side of the same below said keyboard, said frame being provided with rearwardly projecting brackets, pivots attached to said brackets, and a piano action pivotally supported on said pivots on the rear side of said frame below said keyboard.

GUSTAF WALDEMAR LUNDHOLM.
